LIFTER ROOF STORAGE TANK

John W. Allen, Chicago, Ill., assignor to
Chicago Bridge & Iron Company

Application September 13, 1945, Serial No. 615,943

11 Claims. (Cl. 48—176)

1

This invention relates to a lifter roof type storage tank, and particularly to a roof for said tank.

Storage tanks of the lifter roof type are used for storing liquids or gases, and the roof is raised or lowered by pressure of the contents of the tank. Various means have been proposed for sealing the edge of the roof to the inner surface of the tank shell so that the contents will not escape, but many of the structures have been unsatisfactory. In some tanks the seal interfered with movement of the roof, while in others the seal wore out and permitted the tank's contents to leak out.

I have invented a lifter roof for a storage tank that employs a flexible seal between the edge of the roof and the inner surface of the tank shell. This flexible shell is so constructed that the only wear is due to bending, as it does not rub against itself or against the roof and the tank shell when the roof is changing positions. This new roof is also provided with a counterweight which balances the roof against tipping action of any external loads such as wind and snow. This counterweight also balances at least part of the weight of the roof, causing a reduced operating pressure. The counterweight is attached to the tank shell by a cable means running over at least one sheave that is attached to the roof. The counterweight is preferably connected to the tank shell by a plurality of cable means substantially equally spaced around the tank. The counterweight system may be applied to any movable piston-like object although it will be specifically described as applied to the new lifter roof.

The invention will be described as related to a typical embodiment as shown in the accompanying drawings. Of the drawings Fig. 1 is a plan view of the tank; Fig. 2 is a vertical section taken along line 2—2 of Fig. 1 with the roof of the tank in its lowest position; Fig. 3 is a view similar to Fig. 2 with the roof in its highest position; Fig. 4 is an enlarged fragmentary elevation showing a section of the top center of the tank; and Fig. 5 is an enlarged fragmentary elevation showing the top edge of the tank.

The storage tank illustrated in the accompanying drawings includes an outer shell 10 of cylindrical shape and a lifter roof 11 of substantially circular shape located within the shell and extending beyond the sides thereof. Attached to the roof is a vertical cylindrical inner skirt 12 extending down from the roof and within the shell 10. At the outer edge of the roof 11 there is located a downwardly extending cylindrical 55

2

weather skirt 13 on the outside of the shell. This weather skirt is to prevent rain from being blown into the seal. On top of the outer shell 10 there is located a narrow cylindrical back up shell 14 with its lower edge abutting the top edge of the shell 10.

A flexible seal 15 is provided between the roof 11 and the shell 10 of the tank. This flexible seal may be a fabric impregnated with a flexible 10 impervious material such as a synthetic rubber. An excellent synthetic rubber for this purpose is neoprene. The back up shell serves to reinforce the flexible seal when the roof 11 is in its top position.

15 The seal 15 is bolted at one edge to the bottom of the inner skirt 12, and at the other edge is bolted between the back up shell 14 and the main shell 10. The seal extends all around the tank and is wider than the distance between the lines 20 of attachment when this distance is at a maximum. Thus the seal 15 is bowed upward at all times by the pressure of the contents of the tank. Because of this pressure the seal is never permitted to rub against itself as the roof changes 25 positions, and likewise does not rub against the roof or the seal. The arrangement of the seal at the lowest position of the roof is shown in Fig. 2, and its arrangement at the highest position is shown in Fig. 3.

30 A counterweight 16 is attached to the shell 10 by means of cables 17 which pass over sheaves attached to the roof. These cables are substantially equally spaced around the tank and not less than three should be used on any tank. In 35 the embodiment shown six cables are provided.

The counterweight 16 is of cylindrical shape and is housed in a cylindrical well 18 located at substantially the center of the tank and extending through a hole 19 in the center of the roof. 40 The well 18 is supported on the bottom of the tank by a post 20. The well 18 and post 20 are reinforced against lateral movement by means of a plurality of rods 21 extending radially to the shell 10 of the tank. The rods are attached at 45 their inner ends to a circular bearing plate 22 located on the bottom of the well and against which the post 20 bears.

The space between the well 18 and the hole 19 in the center of the roof is sealed by means 50 of a second flexible seal 23. This seal extends around the opening and is also made of a fabric impregnated with an impervious flexible material such as neoprene. It is wider than the greatest distance between its points of attachment to the well 18 and to the edge of the hole 19. The

pressure of the contents of the tank serves to keep it bowed upward at all times, and its action is similar to that of the first seal 15.

In order to prevent water and dirt from getting into the well 18 there is provided a housing 24 attached to the roof and covering the well. This housing is high enough so that its top never touches the top of the well or the cables during the roof's travel.

Each of the cables 17 has its own system of 10 sheaves over which it is extended to the side of the shell. Each cable extends from the counterweight 16 over a first sheave 25 fastened to the top of the well 18, under a second sheave 26 attached to the roof adjacent the well, over a 15 third sheave 27 attached to the edge of the roof, down over a fourth sheave 28 located beneath the third sheave 27 and attached thereto and to the roof by means of an angular bracket 29. From the fourth sheave 28 the cable extends upward 20 to the tank shell and is attached thereto by means of a semicircular eye 30 attached to the shell. The second sheave 26 holds the cable 17 adjacent the roof 11.

When the lifter roof is in its lowest position it is supported by means of a shelf 31 fastened to the inside of the shell 10 and a second shelf 32 fastened to the outside of the well 18. The roof is supported on the first shelf 31 by the inner skirt 12. The second shelf 32 contacts the roof at a surface adjacent the hole 19 surrounding the well 18.

The counterweight system shown and described helps limit pressure on the two flexible seals but its principal purpose is to stabilize the roof and keep it level. If the roof is forced down at one point the strain on the cables adjacent this point becomes greater, and this tends to pull the roof back into position.

In the construction shown in the accompanying drawings the mechanical efficiency of the counterweight and cable system is approximately two when the roof is in an intermediate position between top and bottom. When the roof is near its top position the efficiency is less than two but greater than one. Any mechanical efficiency may be provided by altering the number of sheaves attached to the roof and by changing the point of attachment of each cable to the shell.

The weight of the counterbalance may be equal to or less than the weight of the roof, depending upon the pressure desired in the storage tank. It will not ordinarily be greater than the weight of the roof.

Although the counterweight system has been described in detail as applied to a lifter roof the same system may be applied to any movable piston-like object located in a housing and movable relative thereto. The system has the advantage of stabilizing the object to keep it level and also will balance at least a portion of the weight of the object.

The storage tank shown and described may be used for storing liquids as well as gases. When the tank is to be used for storing liquids the roof will float on top of the liquid without the provision of pontoons; although their use is not precluded.

Having described my invention as related to a typical embodiment of the same, it is my intention that the invention be not limited by the details of description unless otherwise specified, but rather be construed broadly within its spirit and scope as set out in the accompanying claims.

I claim:

1. A storage tank comprising an outer shell, a lifter roof raised and lowered within the circumference of the shell wall by the pressure of the gas within the tank, an annular seal comprising a fabric impregnated with an impervious flexible material having one edge attached to the edge of the roof and having its other edge attached to the shell along a substantially horizontal line around the interior of the shell near the top thereof, the width of said seal between its edges being greater than the distance between the edge of the roof and said line in all positions of the roof whereby the seal is at all times bowed upward by pressure of the contents of the tank, and a counterweight vertically movable in a stationary well at the center of the tank and attached through a cable means to the shell, said cable means including at least two cables, with each cable extending around a plurality of sheaves and passing under at least one sheave attached to the roof, and a flexible seat between the roof and the well.

2. A storage tank comprising an outer shell, a lifter roof raised and lowered within the circumference of the shell wall by the pressure of the gas within the tank, a flexible seal between the outer edge of the roof and the shell, a counterweight at substantially the center of the tank attached through a cable means to the shell, said cable means including at least two cables, with each cable extending around a plurality of sheaves and passing under at least one sheave attached to the roof, a stationary well for housing the counterbalance extending through the roof at substantially the center thereof, and a flexible seal between the well and the center portion of the roof that surrounds the well.

3. The storage tank of claim 2 wherein the seal around the well comprises a fabric impregnated with an impervious flexible material with said seal being wider than the distance between its two points of attachment at all positions of the roof whereby the seal is at all times bowed upward by pressure of the contents of the tank.

4. The storage tank of claim 2 wherein both said seals comprise fabric impregnated with impervious flexible material, said seals being wider than the distances between their respective points of attachment at all positions of the roof whereby the seals are at all times bowed upward by pressure of the contents of the tank.

5. A storage tank comprising an outer shell, a lifter roof raised and lowered within the circumference of the shell wall by the pressure of the gas within the tank, an annular seal comprising a fabric impregnated with an impervious flexible material having one edge attached to the edge of the roof and having its other edge attached to the shell along a substantially horizontal line around the interior of the shell near the top thereof, a counterweight positioned in a stationary well at substantially the center of the tank with the well extending through the roof, a second seal comprising a fabric impregnated with an impervious flexible material extending from the well to the center portion of the roof surrounding the well, both said seals being wider than the distance between their respective points of attachment at all positions of the roof, and a plurality of cables each extending from the counterweight to the outside of the shell around a plurality of sheaves and passing under at least one sheave attached to the roof.

6. The storage tank of claim 5 wherein the

cables are substantially equally spaced around the tank.

7. The storage tank of claim 5 wherein the counterweight is substantially cylindrical and the well is also substantially cylindrical and supported on the floor of the tank.

8. The storage tank of claim 5 wherein each cable extends from the counterweight over a sheave attached to the top of the well, over a second sheave attached to the edge of the roof, down under a third sheave located below the second one and also attached to the roof, and then to a point on the exterior of the tank shell.

9. The storage tank of claim 5 wherein the cables are substantially equally spaced around the tank and each cable extends from the counterweight over a sheave attached to the top of the well, over a second sheave attached to the top of the roof, down under a third sheave located below the second one, and also attached to the roof, and then to a point on the exterior of the tank shell.

10. The storage tank of claim 5 wherein the cables are substantially equally spaced around the tank and each cable extends from the counterweight over a sheave attached to the top of the well, under a second sheave attached to the roof near the well, over a third sheave attached to the outer edge of the roof, down under a fourth sheave located below the third one and also attached to the roof, and then to a point on the exterior of the tank shell, said third and fourth sheaves extending beyond the edge of the tank shell.

11. A counterweight system for a movable piston or the like comprising a piston, a housing

around the piston with said piston movable vertically therein, a weight located substantially in the center of the piston and movable vertically relative thereto, a guide housing at the center of the piston and stationary relative to the piston housing, said guide housing surrounding the weight and extending above the piston with the piston being movable relative to the guide housing, means for sealing the piston to the guide housing, and a plurality of cable means each attached to the weight at one end and to the piston housing at the other end, each of said cable means passing over a sheave attached to the top of the guide housing, under a second sheave attached to the piston near the guide housing, around a third sheave attached to the outer edge of the piston, under a fourth sheave located below the third and also attached to the piston, and finally to the side of the piston housing.
